UNITED STATES PATENT OFFICE.

GEORGE DAMON, OF CRANFORD, NEW JERSEY, AND ELIAS S. PEETS, OF NEW YORK, N. Y., ASSIGNEES, BY MESNE ASSIGNMENTS, TO THE A. N. KELLOGG NEWSPAPER COMPANY, OF CHICAGO, ILLINOIS.

PRODUCING MATRICES FOR STEREOTYPES.

SPECIFICATION forming part of Letters Patent No. 392,189, dated November 6, 1888.

Application filed June 2, 1887. Serial No. 240,087. (No model.)

To all whom it may concern:

Be it known that we, GEORGE DAMON, of Cranford, Union county, New Jersey, and ELIAS S. PEETS, of the city, county, and State 5 of New York, have invented a certain new and useful Matrix for Making Stereotype-Plates and the Process of Manufacturing the Same, of which the following is a specification, reference being had to the drawing accompany- 10 ing and forming a part of the same.

The object of this invention is to produce a cheap matrix or mold for producing stereotype or printing plates which shall be more durable and efficient than those now in use. The 15 main object is to produce at small cost a matrix with a metal face which shall be capable of being used a great number of times for making printing-plates, and which shall remain unimpaired and capable of producing clear 20 and distinct characters during a long period of use. To this end we have produced a metal-faced matrix with a paper or papier-maché backing, the method or process by which we produce the same being in detail as follows:

25 By means of the type or electrotype-plate of the matter which it is desired to reproduce we first take an impression in papier-maché, thus forming a matrix or mold. Stereotype-metal is then poured into the matrix and an ordinary 30 stereotype-plate formed. This plate is then coated with melted wax, which is carefully wiped off from the face of the type, and before the wax has entirely hardened powdered plumbago is dusted over the whole surface. A small quantity of a volatile solvent— 35 such as benzine or alcohol—is then applied to the plate, after which the plate is again wiped carefully and a further coating of plumbago applied to its surface. When thus prepared, 40 the plate is immersed in a copper solution and a film of copper deposited upon its face. In order to prevent the back of the plate from receiving any deposit, it is protected in the usual way by a film of wax or like material. The 45 plate is then removed from the bath to a beating-table and a sheet of dampened stereotype-paper laid over it, which is carefully beaten into the irregular copper surface. There is

next a thin coating of pipe-clay spread over the entire surface, which by any convenient 50 tool is removed from the depressed surfaces of any considerable extent, which occur where paragraphs or blanks are found in the type, and into these depressions are then placed small strips of compressed stereotype-paper 55 properly cut to fit into the same for the purpose of making a more uniform surface, and over the whole are then laid in succession two or more additional sheets of moist stereotype-paper, which are independently beaten into 60 the underlying layer and the surface of the plate. Upon this surface any desired number of dry sheets of paper sufficient in number to form a stiff backing for the plate are laid and beaten in. In practice we have found a dozen 65 to fifteen sheets answer this purpose. The plate is then pressed or rolled in order to smooth the surface, and it is then allowed to thoroughly dry. When brought to this condition, the copper coating, with its backing of 70 paper, may be stripped from the plate, and is in condition for use as a matrix, from which any number of stereotype-plates may be produced and from any of the materials commonly used for this purpose—such as type-metal—or 75 a plastic, such as xylonite, celluloid, or other like substances.

It will thus be seen that the above process involves the following main parts or steps: first, the production of a stereotype-plate, 80 which, it will be understood, may be done by any other process than that described; second, the electro-deposition upon such plate of a film of copper under conditions which permit the ultimate removal of the copper from the surface of the plate without injury to the facing; 85 and, lastly, the re-enforcement of this film by a backing of paper or papier-maché, which intimately adheres to the copper plate, and which strengthens the copper plate and permits it to 90 be readily stripped from the stereotype, and which forms without further treatment the matrix.

The accompanying drawing is appended in further illustration of the invention.

Let A represent a stereotype or electrotype 95

plate. This, as we have before stated, may be produced in any well-known way. When finished, its surface is coated with wax, which is wiped off from the surface of the type. The purpose of this is to afford an even surface for the electro-deposition of the copper or other metal and to fill up the irregularities of surface in the interstices between the lines of type. When the plumbago has been applied, the benzine is added, it having been found that this produces a better distribution of the plumbago surface. To thoroughly coat the type, plumbago is dusted a second time over the plate after the application of the benzine or solvent, and then the copper is deposited. The copper film (designated by B) is shown detached from the stereotype, and the backing with which it is combined is lettered C. This latter is most advantageously applied by the process we have set forth above; but it is evident that this method may be varied to some extent without departure from the invention. The main object is to produce a solid and perfect backing for the copper, in order that the matrix of which it forms the face may be capable of withstanding a very high pressure without becoming impaired by frequent use. This is particularly desirable in case xylonite or a like substance is the material used for making the stereotypes from the matrix. We find that this object is more perfectly secured by the use of the pipe-clay by filling the larger depressions with small pieces of compressed stereotype-paper, and by proceeding in other respects as above indicated.

What we claim is—

1. A matrix for the production of stereotype-plates, composed of a metal facing with a backing of paper or papier-maché, as set forth.
2. The method or process of constructing a matrix for the production of stereotype-plates, which consists in depositing a film of metal upon a stereotype-plate, uniting therewith a

backing of paper or papier-maché, and stripping or removing the film and its backing from the plate, as set forth. 45

3. The method or process of constructing a matrix for the production of stereotype-plates, which consists in coating a stereotype with wax, dusting plumbago thereon, then treating the surface with benzine or its equivalent, then depositing on said surface a film of copper, uniting with the film a backing of paper, and stripping or removing the film and its backing 50 from the plate. 55

4. The method or process of constructing a matrix for the production of stereotype-plates, which consists in coating a stereotype with wax, dusting plumbago thereon, then treating the surface with a volatile solvent, then applying a second coating of plumbago, depositing thereon a film of copper, uniting with the film a backing of paper, and stripping or removing the film and its backing from the plate, 60 65 as described.

5. The method or process of constructing a matrix for the production of stereotype-plates, which consists in depositing on a suitably-prepared stereotype a film of copper, uniting 70 with the said film a backing of paper or papier-maché and pipe-clay, and stripping or removing the film and its backing from the plate, as described.

6. The method or process of constructing a matrix for the production of stereotype-plates, which consists in depositing on the properly-prepared surface of a stereotype a film of metal, uniting with such film a re-enforcing material to form a backing, and stripping or removing 75 the film and its backing from the plate, as set forth. 80

Signed this 24th day of November, 1886.
